UNITED STATES PATENT OFFICE.

MILTON ZUBER, OF NEW YORK, N. Y.

MULTIPLE-SPOOL HOLDER.

Application filed August 12, 1922. Serial No. 581,311.

To all whom it may concern:

Be it known that I, MILTON ZUBER, a citizen of the United States, and resident of New York city, in the county of New York and State of New York, have invented certain new and useful Improvements in Multiple-Spool Holders, of which the following is a specification.

My present invention relates primarily to 10 multiple spool holders, and although it has its preferred application in the textile industry for holding a plurality of spools of thread in convenient position against loss and for convenient access at will to the 15 thread of any selected spool, many of the preferred features are applicable in any relation where access is desired at will to any one of a plurality of reels, spools or other magazines of thread, wire or other material.

It is an object of the invention to provide 20 a spool holder of particularly simple rugged and inexpensive construction for supporting spools without danger of entangling the threads or other material thereon and which shall permit access readily and 25 conveniently to any selected spool.

Another object is to provide a holder of the above type which shall be suited to 30 mounting any desired number of spools in position and in which the spools can be readily removed or replaced when exhausted.

In a preferred embodiment, the spool holder comprises a built up construction, 35 including a plurality of spool support bracket arms mounted upon a support, the spool held at one end by each arm being maintained in position by the coaction of one of the other arms against removal when 40 the device is locked.

In a preferred specific embodiment, the bracket arm members are telescoped over a cylindrical support rod and successive arms are keyed with respect to each other, the 45 arms extending outward from the support rod in a plurality of groups, each group in a common plane, the telescoping bracket portions for each group constituting spacers between successive arms in each other group.

In a preferred inexpensive construction, 50 the support rod is a simple vertical tube, the bracket members are composed of T fittings telescoped over said tube and the bracket arms are pipe elements fitting into the stems 55 of the T fittings and flattened at their outer ends for support of the spools. A lock is

provided above the uppermost of the bracket arms to prevent separation of the keyed connection between successive arms, so that the spool members will all be locked in position and may be released upon opening of the lock member to raise any bracket arm for separation thereof with respect to the associated spool therebelow which can then be removed for replacement.

In the accompanying drawings in which is shown one of various possible embodiments of the several features of the invention,

Fig. 1 is a side elevation with parts 70 broken away of a preferred embodiment of the invention, shown in section, and:

Fig. 2 is a plan view thereof.

Referring now to the drawings, I have shown a spool holder comprising a base, 75 pedestal or support 1 preferably provided with lugs 2 by which it may be screwed to a table, bench or other support. Preferably threaded into the upper end of the base is a support tube or rod 3. In the preferred 80 specific embodiment, a plurality of fittings 4, 5, 6 and 7, 10, 11 and 12, are telescoped over the support rod, each fitting having a key 8 integral therewith in the lower edge thereof fitting into a corresponding key- 85 way 9 in the upper edge of the adjacent fitting immediately therebelow. Fittings 4, 5, 6 and 7 in the specific embodiment are shown as ordinary T fittings, within 90 the stems 13 of which are threaded and secured short lengths of pipe 14 flattened as at 15 near the outer ends thereof to constitute spool supporting platforms. The telescoped fitting 5 which extends toward the left together with the collar fitting 10 95 constitute a spacer between fittings 4 and 6 extending toward the right, to afford the required gap between the free ends of arms 14^a and 14^b for accommodating a spool as at 16. Similarly the telescoped fitting 6 100 with collar fitting 10 constitute a spacer between fittings 5 and 7 for accommodating a spool (not shown) therebetween. Each spool is preferably mounted upon a pin, axle or rod 17 having a head 18 pressed into a corresponding aperture 19 on the flattened portion 15 of the arm therebelow and extends upward therefrom, the upper free tapered end 20 of each pin extending in the 105 assembled construction into a corresponding depression 21 in the lower end of the pin head immediately thereabove. Spool pins 110

of the type described, it will be seen, are secured into the arms of fittings 4, 5, 6 and 7 in the specific embodiment shown.

A special crown fitting 12 is telescoped 5 over the upper end of the rod and has a key connection 22 with the spacer collar 11 immediately thereto. Crown fitting 12 has pipe stem extensions 23 similar to those heretofore described, affording sockets 24 at 10 their ends for coaction with the upper ends of the spool pins 17.

The device described is releasably locked by a lock cap 25 telescoped over the free end of the support rod above the crown fitting 12, the cross pin 26 through the support rod extending into an elongated slot 27 in the cap to limit the elevation thereof. The cap is normally retained in its lowermost or locked position by a spring latch member 20 28 fitting into corresponding notches 29 in the inner wall of the support tube near the upper end thereof, said latches being releasable by means of a key (not shown) insertable through a keyhole 30.

25 It will be seen that the multiple spool support described is of particularly simple and inexpensive construction. The keys and keyways are readily produced by a simple milling operation upon standard T fittings 30 and the flattening of the spool supporting rod extensions is readily effected by means of a punch press operation. It will be readily seen that by inversion of a T fitting for coaction of its keys with a corresponding keyway of an adjacent identical fitting, the arms of said two fittings will extend as shown at 4, 5 in opposite directions from the support rod, as desired.

40 The spool holder, it will be seen, is a built-up construction assembled by telescoping the successive identical T fittings and spacer collars over the support rod, applying the locking cap and as a final operation, applying the lock pin 26 in position. To charge 45 the multiple spool holder, it is merely necessary to release the latch 28, elevate the cap to the limit allowed by the slot 26 which permits elevation of any one of the fittings to release its keyway connection to those 50 thereto, to permit ready displacement thereof about the support rod 3 as an axis to expose the upper end of the spool anchoring pin immediately thereto. By this means, it will be seen that a spool can readily be slipped over each or any required 55 number of the support axles, whereupon the bracket arm immediately thereto can be restored to its original position and when 60 they have all been restored, the cap 25 can be snapped back to locked position. If all of the keys are not in proper coaction with their keyways the locking cap is in a position 65 higher than raised locking position. It will therefore be seen that the locking cap cannot be snapped to locking position until

the parts have been restored to the position shown in Fig. 1.

When the device is locked, each of the keys 8 is locked with respect to the keyway 9 adjacent thereto, so that none of the bracket arms can be rotated with respect to its companion, but any rotation must be of all as a unit. Each support pin protrudes into the corresponding socket of the pin head thereabove and the spools are firmly locked in place and cannot be removed except by axial separation, which is prevented until lock 28 is opened by an authorized person in possession of a key.

In use, the operator grasps the thread on 80 any selected spool and draws thereon in the usual manner for sewing either by machine or by hand. Upon drawing on the thread, the tension thereon will effect rotation of the entire assembly of bracket, support arms 85 and spools about the spool support 3 as an axis to bring the selected spool into most convenient position relative to the operator, without danger of entangling with respect to the threads on the other spools, which 90 maintain their position relative to the selected spool.

In order to prevent spinning of any spool about its axle, it is preferred to provide 95 dished springs 31 encircling axle pins 17, to exert friction or braking force upon each spool, by forcing it against the bracket arm immediately thereto. By this operation, friction will be exerted upon the spool, such that when the tension is applied to the 100 thread thereof, the spool will first be drawn together with the entire assembly of sleeve fittings and projecting arms to the position in which the tensed thread is in the plane 105 of the support rod. By reason of the braking effect of springs 31, tension suddenly applied to the thread will not cause spinning of the spool about the axle and will avoid any consequent danger of entangling 110 the thread.

When a spool is to be replaced after exhaustion thereof or for substitution of a different type or color of thread, the operator opens the lock 28, raises the cap 25, raises the arm 14 immediately above the 115 exhausted spool, thereby releasing the free end of the corresponding spool support axle 17, and after laterally shifting the arm about the support rod, he can remove the spool from its pin. The operation of replacement, resetting and locking the device 120 will be obvious from the foregoing.

The embodiment shown in the drawings is merely a simple preferred form of the invention. It will, of course, be understood 125 that by providing additional fittings and a longer support rod, the spool holder may be built up to any elevation desired. It will be moreover understood that the bracket arms may be extended in three or more planes at 130

corresponding angles. It will also be apparent that, if desired, the entire group of bracket arms and their telescoping portions may be formed as a single integral sleeve 5 about the support rod or may be formed integral with the support rod, the latter, in that case, being preferably rotatable in its base. It will also be seen that the apparatus need not necessarily be employed in vertical 10 position but the support rod may extend horizontally. This relation would in some cases be preferable, particularly where a multiplicity of spools is required.

It will thus be seen that there is herein 15 described apparatus in which the several features of this invention are embodied, and which apparatus in its action attains the various objects of the invention and is well suited to meet requirements of practical use.

20 As many changes could be made in the above construction and many apparently widely different embodiments of this invention could be made without departing from the scope thereof, it is intended that all matter 25 contained in the above description or shown in the accompanying drawings shall be interpreted as illustrative and not in a limiting sense.

Having thus described my invention, what 30 I claim as new and desire to secure by Letters Patent of the United States is:—

1. In a multiple spool holder, in combination, a vertical support rod, and a plurality 35 of spool brackets mounted on said rod and extending at an angle thereto, each said bracket having mounting means near its outer end for a spool, and means to prevent undesired removal of each spool from its support.

40 2. The combination set forth in claim 1 in which each bracket is rotatable about the support as an axis to dispose the spool in use in convenient position.

3. In a spool holder, in combination, a 45 support rod, a plurality of bracket members telescoped over said rod, each said bracket member having an arm extending outward from said rod, a support pin near the outer end of each arm for mounting a spool, said telescoped support brackets being rotatable about said support rod to dispose any selected spool in convenient position for use.

4. In a multiple spool holder, in combination, a support rod, sleeve means thereon 55 having a plurality of brackets projecting outward therefrom at right angles to the rod, each said bracket having a pin thereon parallel to said rod affording a mount for a spool, and means to maintain all of said spools against inadvertent removal from said support, said sleeve means being rotatable about said support rod as an axis to bring it to most convenient position for use.

5. A multiple spool holder comprising a 60 base, a rod, a plurality of bracket arms ex-

tending outwardly at right angles to said rod, one set of said arms extending in a common plane, spool holding pins secured near the outer ends of said brackets and extending parallel to said rod, the free end of 70 each said spool holding pin being restrained against displacement by the bracket arm adjacent thereto, and releasable means to lock said spools against removal from said bracket arms. 75

6. In a multiple spool holder, in combination, a base, a support rod extending vertically therefrom and a plurality of bracket members arranged to slide for a limited range along said rod and rotatable thereabout, each of said brackets having a pin rigid therewith and extending upward therefrom, each of said brackets between the upper and lower ends serving concurrently as a retaining member for the upper end of 80 the spool support pin therebelow and as a holding member for the support pin thereabove.

7. In a multiple spool holder, in combination, a support rod, a plurality of bracket 85 arms telescoped thereover and normally extending at right angles therefrom in a common plane, each of said arms below the upper one having an upstanding spool support pin parallel to said rod, and a depression 90 the free end of each said pin coacting with the corresponding depression in the arm immediately thereabove, releasable means locking said arms against longitudinal and relative rotational displacement, 95 whereby upon releasing said means, the end of any spool holding pin may be separated from the arm retaining the same and said arm rotated about the support relative to the arm therebelow to permit removal and renewal of a spool. 100

8. In a multiple spool holder, in combination, a support rod, a plurality of bracket arms telescoped over said rod, said arms being arranged in a plurality of groups, each group extending in a fixed direction from said rod and in a common plane, means extending between successive arms in each plane to secure a spool therebetween, and releasable means to lock all spools in fixed position. 110

9. In a multiple spool holder, in combination, a support rod, a plurality of spool supporting brackets telescoped thereon, said brackets having arms extending in a common plane outward from said rod, spool support pins parallel to said support rod, extending between successive arms, means retaining said arms in a common plane and releasable means for freeing said arms with respect to each other to permit axial displacement of any said arm from an adjacent spool support pin and rotation thereof about the support rod for removal and replacement of a spool. 120

10. In a multiple spool holder, in combina- 125

tion, a support rod, a succession of bracket members telescoped over said rod and keyed with respect to each other for rotation there-
5 of about said rods as a unit, spool support arms rigid with some of said brackets, ex-
tending outward from said arms and in a common plane, each said arm having a spool support pin extending near the free end thereof, parallel to said support rod, each
10 said arm above the lowermost one having socket means telescoping over the free end of the spool support pin therebelow, and lock means for locking said bracket members and spools, whereby upon releasing said lock
15 means, any key means between successive bracket members may be separated and the corresponding bracket arm elevated with respect to the upper end of the pin therebelow and rotated about the support rod as an axis
20 to free the corresponding spool for removal or replacement.

11. In a multiple spool support, in combination, a rod, a plurality of bracket members telescoped over said rod, each said
25 bracket member having an arm extending outward from said rod, said arms extending in different planes in a definite cyclic order to form a plurality of groups, each group ex-
30 tending in a common plane, means for securing a spool against inadvertent removal from between each pair of successive arms in a common plane, key means retaining said successive telescoped bracket elements against relative rotation and releasable
35 means to prevent displacement of any bracket member along a rod.

12. The combination set forth in claim 11 in which the telescoped bracket members are
40 freely rotatable about the rod and are keyed together at their abutting surfaces, whereby any spool may be readily drawn by rotation of the entire assembly of bracket arms and spools about the support rod to bring it into
45 convenient position for use.

13. A built-up multiple spool holder comprising a base, a support rod projecting therefrom, a plurality of spool bracket arms telescoped over said support rod, rotatable thereabout and keyed together, pin means
50 locked between each pair of arms at the same side of the support rod for maintaining a spool therebetween, lock means for maintaining said keyed arm members against longitudinal displacement with respect to each other and thereby maintaining the spools against removal, whereby in use, the entire assembly of arms may be rotated about the spool support rod as an axis to bring any desired spool into convenient position, whereby upon releasing the lock
55 means any arm may be elevated to release its keyed connection to the arms therebelow

and also to separate it from the spool there-
60 below, whereby upon subsequent rotation of said arm about said support rod as an axis, 65 the spool may be removed for replacement.

14. In a multiple support fixture for spools, in combination, a support rod, a plurality of T fittings telescoped over said rod, each having a keyway in one edge and
65 an integral key in the other edge coacting with the corresponding keyway in the adjoining T fitting, pipe fitting elements fitting in the stems of said T fittings, and
70 spool support axle pins rigidly secured near the outer ends of said pipe fittings and ex-
75 tends parallel to said support rod.

15. In a multiple spool support, in combi-
80 nation, a base, a vertical cylindrical support pipe, a plurality of T fittings telescoped over said rod, each said T fitting having a pipe rigidly maintained in the stem thereof and flattened near its outer end and a de-
85 pression therein and a spool support pin rigidly secured to each said flattened end and extending parallel to said support rod, the free end of each said pin member extending into the corresponding depression associated with the arm immediately thereabove, and lock means above the uppermost of said
90 fittings to maintain the same against separation from each other longitudinally of the rod.

16. In a multiple spool holder, in combi-
95 nation, a base, a vertical support rod, a plurality of parallel bracket arms telescoped over said rod for support of spools there-
100 between, and spacing means telescoped over said support rod between successive bracket arms.

17. In a multiple spool holder, in combi-
105 nation, a base, a vertical support rod, a plurality of parallel arms rotatable about said rod for support of spools therebetween, and spacers telescoped over said rod intermediate successive arms, said spacers having further arms projecting outward therefrom for supporting a further group of spools.

18. In a multiple spool holder, in combi-
110 nation, a support axle, spool holding bracket arms projecting outwardly there-
115 from and rotatable thereabout as a unit, and means applying friction to each spool with respect to an adjoining arm, whereby upon drawing upon the thread of any spool, the unitary bracket arms will rotate about the spool support rod as a unit to bring the selected spool into convenient position, and whereby spinning of the spool in operation
120 is avoided.

Signed at New York, in the county of New York and State of New York.

MILTON ZUBER.
